UNITED STATES PATENT OFFICE

167,742

RADIO CABINET

Arnold R. Dahlberg, Minneapolis, Minn., assignor
to The Dahlberg Company, Minneapolis, Minn.,
a corporation of Minnesota

Application October 5, 1951, Serial No. 16,843

Term of patent 14 years

(Cl. D56—4)

To all whom it may concern:

Be it known that I, Arnold R. Dahlberg, a citizen of the United States, residing at Minneapolis, in the county of Hennepin and State of Minnesota, have invented a new, original, and ornamental Design for a Radio Cabinet, of which the following is a specification, reference being had to the accompanying drawings, forming part thereof.

Referring to the drawings:

Fig. 1 is a view in perspective of a radio cabinet, showing my new design;

Fig. 2 is a view in end elevation, as seen from the left of Fig. 1;

Fig. 3 is a top plan view; and

Fig. 4 is a view in end elevation, as seen from the right with respect to Fig. 1.

I claim:

The ornamental design for a radio cabinet, as shown.

ARNOLD R. DAHLBERG.
